UNITED STATES PATENT OFFICE.

WILLIAM A. MILES, OF COPAKE IRON WORKS, NEW YORK.

CONDENSER FOR STEAM-PUMPS.

SPECIFICATION forming part of Letters Patent No. 271,096, dated January 23, 1883

Application filed December 21, 1882. (No model.)

To all whom it may concern:

Be it known that I, WILLIAM A. MILES, of Copake Iron Works, in the county of Columbia and State of New York, have invented an Improvement in Condensers for Steam-Pumps, of which the following is a specification.

Steam-pumps have been operated by direct-acting engines very extensively, and in some instances efforts have been made to condense the steam from such engines; but where the water-pump has acted as the condensation-pump there is difficulty in maintaining the necessary vacuum in the pump, and also in obtaining a useful vacuum behind the piston of the engine, and when the engine is running slow there is a risk of the steam condensing and allowing the water to rush into the steam-cylinder.

My invention relates to the combination, with the suction-pipe leading to the pump, of a steam-pipe for the exhaust from the engine opening into the suction-pipe, and a valve applied at the said steam-pipe to prevent the water passing into the same. Hence when the vacuum in the suction-pipe is greater than the vacuum at the exhaust the valve will open and the steam will pass into the water and be condensed; but when the vacuum in the exhaust-steam pipe is the greatest the valve will close. I also arrange the suction-pipe in such a manner as to obtain any desired amount of vacuum without materially increasing the work of the pump in lifting the water from one level to another.

There are numerous ways in which the valve and steam-pipes may be arranged and constructed. Some of these will form the subject of separate applications. The present case is to be regarded as relating to the aforesaid features, broadly.

In the drawings I have shown, in Figure 1, a vertical section of the said improvement. Fig. 2 is a similar view of the valve in a slightly modified form, and Fig. 3 is a plan of the same.

The pipe *a* is the inlet through which the water is drawn, and *b* represents a pipe leading to the pump. I prefer to make use of the siphon-legs *c d*, the first being a continuation of the pipe *a*, the second intersecting the pipe *b*. There is a check-valve at *e* and a three-

way cock at *f*. When the pump is started the three-way cock is to be placed in the position shown by dotted lines in Fig. 1, and closes the siphon-leg *d*, and allows the water to be drawn up *a* into *b* and thence to the pump. The cock *f* is now gradually turned, and the air exhausted from *c d* passes to the pump. The water rises in *c* past the check-valve *e* and fills both *c* and *d*, and when this is accomplished the valve *f* is turned to close the passage between *a* and *b*, as shown by full lines, Fig. 1, and cause the water to flow by *c d* to *b* to the pump. The water in the legs *c d* balances, and there is but little extra power exerted in the pump to draw the water over this siphon; but the vacuum at the upper part of *c d* is greater than it is at the level of *b*. Hence a better effect will be produced in condensing the steam that passes from the engine by the pipe *g* into the upper part of *c* or *d*. If the column of water in the pipe *a* should be only, say, five feet, there would only be about one-third of a vacuum—say ten pounds pressure; but if the siphon-leg *c* and pipe *a* should be twenty-five feet long there would be about five-sixths of a vacuum, equal to about two and a half pounds pressure, and the column *d*, acting upon the principle of the siphon, counterbalances the weight of the column in *c*, and the pump itself only has to raise the water to the level of *b* and overcome friction.

The steam from the engine is admitted by the pipe *g*, and in this pipe there is a valve, *i*, for preventing the water following up the steam and condensing it in said pipe *h* when the engine is running slowly. This valve may be of any desired character, and the steam-pipe may pass into the uptake *c* of the siphon; but I prefer to place the same in the downflow *d*, as shown. The valve *i* is represented as closing upwardly into the flaring mouth of the pipe *g*, and the stem of said valve is guided by bridges, and the weight of the valve is sustained by the spring *k*. This valve opens and lets the steam out into the water whenever the vacuum in the upper part of the pipes *c d* is greater than the vacuum in the steam-pipe, and when the vacuum in the steam-pipe is the greatest the valve closes.

If it is desired to place the steam-pipe and

valve in the uptake-pipe *c*, the parts should be made as seen in Figs. 2 and 3. In this instance the valve *i* is annular and connected to the stem *l* by arms, the steam-pipe *g* terminating in an annular passage, *h*, which the valve *i* covers. This annular steam-passage should be supported by arms *m*, that pass off to a ring that rests in a seat at the joint between the pipes *c*. In this form of valve, the water passing through the steam-ring as well as around it, the condensing action is increased. In all instances it is important that the openings for the steam to pass through as it issues into the water be narrow, so that the steam will be 15 condensed rapidly by the water. In cases where there is a valve that is opened by the flow of water the steamway, if it is in any manner influenced by such valve, will be opened so that water can pass into the steam-space.

20 I claim as my invention—

1. The combination, with the suction-pipe in a water-raising apparatus, of a steam-pipe through which steam from an engine is discharged, and a valve to be opened by the steam 25 and close in the other direction, substantially as set forth.

2. The combination, with the suction-pipe in a water-raising apparatus, of a siphon extending above the outlet-pipe to the pump, and a pipe discharging exhaust-steam into the 30 siphon near the upper part thereof, substantially as and for the purposes set forth.

3. The combination, with the suction-pipe *a* *b*, of the siphon-pipes *c* *d*, check-valves *e*, three-way valve *f*, and exhaust-steam pipe opening 35 into the siphon-pipe, substantially as set forth.

4. The combination, with the suction-pipe in a water-raising apparatus, of a siphon extending above the outlet-pipe, an exhaust-steam pipe opening into the suction-pipe, and 40 a valve applied to the steam-pipe opening by the steam and closing in the opposite direction, substantially as set forth.

Signed by me this 16th day of December, A. D. 1882.

WILLIAM A. MILES.
